CARBURETOR

Michael Sninsky, Boston, Pa.

Application January 23, 1942, Serial No. 427,995

6 Claims. (Cl. 48—180)

This invention relates to carburetors, and more particularly to a device employed in connection with a fuel vaporizing unit of the character which will vaporize fuel of different grades.

The primary object of this invention is the provision of a device for receiving gaseous fuel from the vaporizing unit and mix therewith air to provide a highly combustible fuel mixture and introduce said fuel mixture into an internal combustion engine in controlled amounts and in condition to produce a maximum horse power development by the engine with carbon deposit reduced to a minimum.

With these and other objects in view as will become more apparent as the description proceeds, the invention consists in certain novel features of construction, combination and arrangement of parts as will be hereinafter more fully described and claimed.

For a complete understanding of my invention, reference is to be had to the following description and accompanying drawings, in which

Figure 1 is a side elevation illustrating a device constructed in accordance with my invention.

Figure 2 is a vertical sectional view illustrating the device.

Figure 3 is a sectional view taken on the line 3—3 of Figure 1.

Figure 4 is a sectional view taken on the line 4—4 of Figure 1.

Referring in detail to the drawings, the numeral 5 indicates the body of the device which is of elongated formation and includes companion sections detachably connected by fasteners 6. The body 5 has a bore 7 extending from end to end thereof. One end of the body is shaped to provide an attaching flange 8 adaptable to an intake manifold of an internal combustion engine. The other end of the body is in the form of a flange, as shown at 9, to form a base portion for an air filter 10. The latter-named end of the body also has integral therewith a skeleton type abutment 11 to which a removable cover plate 12 is secured by a fastener 13.

The opposing faces of the cover plate 12 and base 9 are provided with annular grooves 14 in which are seated annular filtering elements 15 of foraminous material. Filtering material 16 is also positioned between the filtering elements 15 and the base 9 and cover plate 12. The air passing through the filtering material and filtering elements will be relieved of dirt and other foreign matter before entering the bore 7 of the body 5.

Formed in the body 5 and spaced from each other and bisecting the bore 7 are valve seats 17

and 18 of spherical shape in which are journaled valve elements 19 and 20 of spherical shape to match the seats and control the passage or bore 7 of the body. The valve elements have formed thereon oppositely disposed pintles 21 journaled in the body and one of the pintles of the valve element 19 extends exteriorly of the body and is bent angularly to form an arm 22 to which a throttle control mechanism may be pivotally connected. The valve elements 19 and 20 are tied together for movement in unison on their pivots. The tie between the valve elements is in the form of a connecting link 23 pivoted to the valve elements, as shown at 24.

By reference to Figure 3 it will be seen that the seats of the valve elements are cut through one of the walls of the body to permit the connecting link 23 to operate exteriorly of the body. A removable cover plate 25 is secured on the body by fasteners 26 to overlie the link 23 and its pivotal connection to the valve elements to protect them against damage and interference by other objects, also to close the seats where they extend through one wall of the body.

The valve elements 19 and 20 are provided with oppositely arranged main ports 27 to be moved into and out of communication with the bore 7 for the purpose of controlling the flow of fuel therethrough.

The valve element 20 is provided with opposed fuel ports 28 to be moved into and out of registration with fuel ports 29 formed in fuel chambers 30. The fuel chambers are arranged to extend horizontally in opposite directions from the valve seat 18 in the form of substantially cylindrical extensions having their outer ends reduced and internally screw threaded, as shown at 31, to which pipes or conduits (not shown) leading from a vaporizing unit may be connected to the fuel chambers.

Located in the fuel chambers are cutoff valves 32.

A fuel passage 33 is formed in the body 5 and leads from one of the fuel chambers 30 to the seat 17. A fuel passage 34 is formed in the body and leads from the seat 17 to the bore 7 between the intake manifold of the engine and the valve element 19. The passage 34 is controlled by a needle valve 35. The valve element 19 has ports 36 which move into and out of registration with the passages 33 and 34 and connect with said passages when the valve element 19 is in a position of closing the bore 7 to the intake manifold of the engine so that sufficient fuel may be introduced into the bore 7 between the valve ele-

ment and the intake manifold of the engine to sustain the latter operating at idling speed.

An inwardly opening check valve 37 is located in the bore 7 between the valve element 20 and the air filter. Also located in the bore 7 of the body between the check valve 37 and the air filter is a choke valve 38. The choke valve may be operated in any well known manner for regulating the amount of air into the bore 7 under the suction of the engine when starting the latter.

It is to be understood that vaporized fuel is admitted to the fuel chambers 30 from a vaporizing unit (not shown) and which will form the subject matter of a later application for United States patent. Therefore, it will be seen that in operation the vaporized fuel of the fuel chambers 30 will be admitted to the bore 7 in controlled amounts by the valve element 20. Said valve element also regulates the amount of air received through the filter. The gaseous fuel and air mixed together within the valve element are passed therefrom from the portion of the bore 7 lying between the valve elements 19 and 20 and through the valve element 19 to the intake manifold of the engine. The valve element 19 acts to control the amount of fuel mixture, consisting of the gaseous fuel and air, to the engine. Also it will be seen that the valve element 19 when closed or substantially closed will have its ports 36 in communication with the passages 33 and 34 to admit sufficient gaseous fuel to the engine to sustain the engine at operation at idling speed. The valve elements besides controlling the flow of fuel to the engine also provide mediums of mixing air with the gaseous fuel so that when the mixed fuel enters the engine it will be in a highly combustible condition for the operation of the engine at maximum horse power with a minimum formation of carbon deposits.

From the foregoing description taken in connection with the accompanying drawings it will be seen that the valve element 19 and its seat act as a throttle valve while the valve element 20 and its seat act to control the gaseous fuel into the bore 7 as well as controlling the amount of air to the gaseous fuel.

While I have shown and described the preferred embodiment of my invention, it is to be understood that minor changes in construction, combination and arrangement of parts may be made without departing from the spirit and scope of the invention as claimed.

Having thus described the invention, what I claim is:

1. In a device of the class described, an elongated body having one end adapted for connection to a fuel intake of an internal combustion engine, said body having a bore extending from end to end thereof, a throttle valve operating in said bore and carried by the body, a fuel chamber on said body adapted for connection to a gaseous fuel source, a second valve in said body for controlling gaseous fuel from the chamber to the bore and atmospheric air to the bore, tie means between said valves for the movement thereof in unison, means whereby said throttle valve may be actuated by a control means, said body having a fuel passage connecting with the bore between the throttle valve and the fuel chamber and controlled by the throttle valve for sustaining the engine operating at idling speed, and a

needle valve for the further control of fuel through said passage to the bore.

2. In a device of the class described, an elongated body having a bore extending from end to end thereof, means on one end of said body for adapting the latter to a fuel intake of an internal combustion engine, said body having spaced spherical shaped valve seats bisecting the bore, spherical shaped valve elements, journaled in said body and coacting with the seats in controlling the bore and provided with opposed ports, gaseous fuel chambers on said body and having ports intersecting one of the seats, the valve element of the latter-named seat having ports for controlling the gaseous fuel therein and to the bore and said latter-named valve element acting as a medium for mixing atmospheric air and the gaseous fuel together, and means for operating said valves.
3. In a device of the class described, an elongated body having a bore extending from end to end thereof, means on one end of said body for adapting the latter to a fuel intake of an internal combustion engine, said body having spaced spherical shaped valve seats bisecting the bore, spherical shaped valve elements journaled in said body and coacting with the seats in controlling the bore and provided with opposed ports, gaseous fuel chambers on said body and having ports intersecting one of the seats, the valve element of the latter-named seat having ports for controlling the gaseous fuel therein and to the bore and said latter-named valve element acting as a medium for mixing atmospheric air and the gaseous fuel together, a connecting link pivoted to the valve elements to cause the latter to move in unison, and means for connecting one of said valve elements to an operating medium.
4. In a device of the class described, an elongated body having a bore extending from end to end thereof, means on one end of said body for adapting the latter to a fuel intake of an internal combustion engine, said body having spaced spherical shaped valve seats bisecting the bore, spherical shaped valve elements journaled in said body and coacting with the seats in controlling the bore and provided with opposed ports, gaseous fuel chambers on said body and having ports intersecting one of the seats, the valve element of the latter-named seat having ports for controlling the gaseous fuel therein and to the bore and said latter-named valve element acting as a medium for mixing atmospheric air and the gaseous fuel together, a connecting link pivoted to the valve elements to cause the latter to move in unison, means for connecting one of said valve elements to an operating medium, and an inwardly opening check valve located in the bore between one of the valve elements and one end of the bore.
5. In a device of the class described, an elongated body having a bore extending from end to end thereof, means on one end of said body for adapting the latter to a fuel intake of an internal combustion engine, said body having spaced spherical shaped valve seats bisecting the bore, spherical shaped valve elements journaled in said body and coacting with the seats in controlling the bore and provided with opposed ports, gaseous fuel chambers on said body and having ports intersecting one of the seats, the valve element of the latter-named seat having ports for controlling the gaseous fuel therein and to the bore and said latter-named valve element acting as a medium for mixing atmospheric air

and the gaseous fuel together, a connecting link pivoted to the valve elements to cause the latter to move in unison, means for connecting one of said valve elements to an operating medium, an inwardly opening check valve located in the bore between one of the valve elements and one end of the bore, and a choke valve located in the bore between said check valve and one end of the bore.

6. In a device of the class described, an elongated body having a bore extending from end to end thereof, means on one end of said body for adapting the latter to a fuel intake of an internal combustion engine, said body having spaced spherical shaped valve seats bisecting the bore, spherical shaped valve elements journaled in said body and coacting with the seats in controlling the bore and provided with opposed ports, gaseous fuel chambers on said body and having ports intersecting one of the seats, the valve element of the latter-named seat having ports for control-

ling the gaseous fuel therein and to the bore and said latter-named valve element acting as medium for mixing atmospheric air and the gaseous fuel together, a connecting link pivoted to the 5 valve elements to cause the latter to move in unison, means for connecting one of said valve elements to an operating medium, an inwardly opening check valve located in the bore between one of the valve elements and one end of the bore, and a choke valve located in the bore between 10 said check valve and one end of the bore, said body having a fuel passage connecting with the bore between one of the valve elements and the fuel intake of the engine and connected to one 15 of the fuel chambers, a needle valve for the control of said fuel passage, one of said valve elements having ports for controlling the fuel passage.

MICHAEL SNINSKY.
